DECORATIVE ARTICLE

Irene M. Casey, Oakland, Calif.

Application December 31, 1936, Serial No. 118,599

7 Claims. (Cl. 41—10)

The invention relates to articles used for ornamental and decorative purposes.

An object of the invention is to provide an article of the character described which may be constructed of a plurality of sheets of material and wherein advantage is taken of the qualities of certain materials and forms and wherein the sheets are assembled in a manner producing a most pleasing, attractive and decorative article.

Another object of the invention is to provide an article of the character described which may be assembled in various forms and adaptations including tree shaped constructions, wreaths, window trimming streamers and the like.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a side elevation of a decorative article constructed in accordance with the present invention.

Figure 2 is a side elevation of a part of the assembled article shown in Figure 1.

Figure 3 is a plan view of a sheet or blank of material used in the present article.

Figure 4 is a side elevation showing the folded form of the sheet illustrated in Figure 3.

Figure 5 is a fragmentary side elevation of a portion of the base support of the article.

The decorative article of the present invention comprises an elongated stem-like central support 6 about which are mounted a plurality of folded sheets 7 and which are of a material and are so folded and secured to the member 7 as to produce an attractive, decorative display. The sheets themselves are preferably rectangular and preferably substantially square and each is folded by gathering a central portion 8 of the sheet so as to draw the corners and peripheral portions of the sheet towards each other. In accordance with the present invention, the portion 8 is so gathered and the remaining portions so folded that the outer peripheral portions 9 will be smoothly rolled in substantially uncreased form and with the corners 11, 12, 13 and 14 of the sheet spaced transversely from one another. The sheets are mounted to the member 7 by twisting

the gathered portion 8 to form a substantially flat tab and the latter is bent at substantially right angles from the remainder of the sheet and placed against the member 6 and secured thereto by any suitable means. The folded sheets are positioned in circumferentially spaced relation around the member 6 and in abutting relation longitudinally of the member with the extending corners of the sheets preferably staggered relative to one another so as to produce a relatively solid mass of folded sheets. As will be understood, by reason of the substantially complete absence of any tight creases in the sheets adjacent their outer periphery, and on the contrary the provision of open rolled portions on these sheets, the assemblage takes on, even though constructed of relatively flexible paper or the like, a considerably increased strength and resiliency in mass form, whereby not only is the appearance of the assembly substantially solid, but the assembly, is in fact quite rugged and sturdy.

As one of the important features of the invention, the sheets are formed of a material which has sufficient toughness and plasticity as to enable a gathering of the center portion of the sheet and folding of the sheet as aforesaid, and a twisting of the gathered center portion without tearing the sheet or throwing the outer peripheral portions of the sheet into sharply formed creases. Also in order that the folded sheets will have a certain sturdiness in assemblage, the material should have moderate resiliency. In addition, from an ornamental display standpoint, it is desirable that the sheets be at least partially transparent or translucent and have good light reflecting surface so as to produce an attractive sheen and brilliance at the exposed surfaces. I have found that the most suitable material for forming the sheets is a cellulose base, fiberless sheet of the class of materials including such trade products as "cellophane" and celluloid and the like. However, certain types of fibrous papers may be used particularly where the paper is treated with wax or oil preparations so as to increase its toughness and plasticity.

As will be clear, the member 6 may be of substantially any length or configuration desired in order to affect substantially any desired shape of the article. Thus, the article may be used in the form of streamers or the like in store windows or draped around various other articles, or with the member 6 substantially circular in form, an attractive wreath may be obtained. In the present showing the article is developed to

produce a decorative tree such as a Christmas tree or the like, and the member 6 is in the form of a relatively thin stem which is mounted to a base support 16 and held in upright position 5 thereby. To produce the desired tree shape the sheets are graduated in size so as to produce a variation in transverse extension from the member 6 along the length thereof and the sheets arranged with a progression in size from the upper 10 end 17 of the member 6 to the base support 16. Preferably the folded portions 8 of the various sheets are bound to the member 6 by a continuous length of adhesive tape 18 or the like which encompasses the portions 8 of the sheets 15 and is wound in spiral manner starting with the smaller sheets at the upper end 17 and extending spirally down the length of the member 6 to embrace the folded portions 8 of the successively added sheets. Surrounding the member 7 adjacent 20 the bottom thereof and supported on the base 16 is a vertically extending collar or tube 19 which is split at its upper end to define a plurality of radially and upwardly extending arms 21 which serve to engage and support the under side 25 of the lowermost row of sheets on the member 6. The member 19 may be formed of card-board or other suitable material and, as will be understood, the bending of the arms 21 from the member provides for a firm resilient support for the 30 bottom row of sheets which in turn support the sheets super-imposed thereabove.

If desired certain Christmas tree ornaments 35 22, such as metallic balls or the like may be added to the tree by supporting the base securing portion 23 of the balls from the center member 6 or securing such portions as here shown directly to the sheets themselves. The balls are preferably inserted between the sheets so that while clearly visible, they will not protrude from the tree but will be compactly and attractively contained within the confines of the tree.

I claim:

1. A decorative article of the character described comprising, an elongated center support, and a plurality of sheets of material each folded by gathering the sheet at substantially the center portion thereof with the outer portions of the sheet folded in rolled substantially uncreased form and secured at said gathered portions to said member in circumferentially spaced relation around said member and in substantially abutting relation along the length of said member.

2. A decorative article of the character described comprising, an elongated center support, and a plurality of substantially square sheets of material each folded by gathering the sheets at substantially the center portion thereof with the outer portions of the sheet disposed in curved substantially uncreased form and with the corners of the sheet spaced transversely from each other, said sheets being secured at said gathered portions to said member in circumferentially spaced relation around said member and arranged in substantially abutting rows along the length of said member.

3. A decorative article of the character described comprising, an elongated center support, and a plurality of sheets of a tough, yieldable, transparent, cellulose base fiberless material each

folded by gathering the sheet at substantially the center portion thereof with the outer portion of the sheet folded in rolled substantially uncreased form, said sheets being secured at the gathered portions thereof to said member in circumferentially spaced relation around said member and in substantially abutting relation along the length of said member. 5

4. A decorative tree shaped article comprising, a base support, an upright member secured thereto and supported thereby, and a plurality of sheets of various sizes and each folded by gathering the sheet at substantially the center portion thereof and secured at the gathered portions of the sheets to said member in circumferentially spaced relation around said member and graduated in size along the length of said member with the sheets progressing in size in the direction of said base support. 10

5. A decorative tree shaped article comprising, a base support, an upright member secured thereto, and a plurality of spaced substantially square sheets of various sizes and each folded by gathering the sheet at substantially the center portion thereof with the outer portions of the sheet disposed in rolled substantially uncreased form and with the corners of the sheet spaced from each other, said sheets being secured at said gathered portions to said member in circumferentially spaced relation around said member 25 and in substantially abutting relation lengthwise of said member, said sheets being graduated in size along the length of said member with the sheets progressing in size in the direction of said base support. 30

6. A decorative tree shaped article comprising, a base support, an upright member secured thereto, a plurality of substantially square sheets of various sizes and each folded by gathering the sheet at substantially the center portion thereof 40 with the outer portions of the sheet disposed in rolled substantially uncreased form and with the corners of the sheet spaced from each other, said gathered center portions being bent at substantially right angles to the remainder of the folded 45 sheet portion and mounted in substantially parallel relation against said member with said folded sheets disposed in circumferentially spaced relation around said member and in substantially abutting relation longitudinally of said 50 member, and means wound as a continuous spiral length around said sheet portions and said member to secure said sheets to said member.

7. A decorative tree shaped article comprising, a base support, an upright member secured thereto and supported thereby, a plurality of sheets of various sizes and each folded by gathering the sheet at substantially the center portion thereof and secured at the gathered portions of the sheets to said member in circumferentially spaced relation around said member and graduated in size along the length of said member with the sheets progressing in size in the direction of said base support, and means mounted on said base support and having a plurality of portions radially 60 extending from said member and engaging under and supporting certain of the bottom sheets of the article. 65
